TOY SMOKE-PRODUCING APPARATUS

Frank Pettit, Union, N. J., assignor to The Lionel Corporation, New York, N. Y., a corporation of New York

Application December 16, 1947, Serial No. 792,108

6 Claims. (Cl. 46—9)

1

The present invention relates to toy smoke-producing apparatus and is more particularly directed toward the production of smoke in toy locomotives.

To create the illusion of the ordinary puffing steam locomotive it is desirable to provide means in the locomotive for producing puffs of smoke or smoke-like material so that the operation of the locomotive will be more realistic as it travels along the track.

The present invention contemplates an improved smoke-producing apparatus according to which the smoke-producing material is carried in a substantially closed electrically heated retort and means are provided for producing intermittent blasts of air which are directed into the smoke vapors in the retort so that some of them are expelled through an upwardly extending flue.

The present invention contemplates an air pump operable by the moving locomotive and acting to produce intermittent air jets which are transmitted to the smoke chamber while no return of flow of air from the smoke chamber toward the pump is possible during the suction stroke of the pump.

Other and further objects will appear as the description proceeds.

The accompanying drawings show, for purposes of illustrating the present invention, one embodiment in which the invention may take form, it being understood that the drawings are illustrative of the invention rather than limiting the same.

In the drawings:

Figure 1 is a vertical longitudinal sectional view through the front part of a toy locomotive showing the smoke-producing apparatus.

Figure 2 is a top plan view with parts in section along the line 2—2 of Figure 1; and

Figure 3 is an exploded vertical sectional view taken on the line 3—3 of Figure 2.

The locomotive is provided with a chassis or body 10 of any convenient type. A pair of driving wheels indicated at 11, 11 is carried on an axle 12 which carries a cam 13 adapted to engage a bent lever 14 anchored at its left end as indicated at 15. This lever is received in a slot 17 in the body 10 and is adapted to be shifted from the full line to the dotted line positions as the cam revolves.

The smoke unit is secured near the front of the locomotive, it being carried by a bracket 20 as indicated. This bracket carries a downwardly opening cylinder 21 and the cylinder receives an inverted cup-like piston 22 which rests on the

free end 23 of the lever 14. The upper end of the piston and the bracket are apertured as indicated at 24 so that on the up stroke of the piston a strong jet of air is forced out through these apertures.

The bracket carries a die cast housing 25 which has a central boss 26 to space the bottom wall 27 of the housing above the bracket. The housing has a cup-shaped receiver 28 and a hole 29 aligned with the holes 24 and extending from the bottom face 27 of the housing to the top. This hole is preferably tapered as indicated in the drawing. A sheet of insulation 30 extends across the bottom of the receiver. A resistance heater 31 is mounted above this sheet of insulation and sheet metal lead-in strips 32, 32 extend out through notches 33 in the outer wall of the housing. These strips are covered with insulation. A sheet metal cover fits tightly about the upper part of the housing. This cover has a flue opening 35 of reduced diameter. It is received in the cover 36 of the locomotive.

A pellet of smoke-producing material such as a wax, which will melt when heated, may be dropped through the flue. This material should be of such a nature that it will not impair resistance heaters at the high temperature required for volatilization. The heating current received from the locomotive circuit will act to volatilize this material and produce a volume of smoke vapors in the retort. These do not readily escape because the small hole 29 does not provide enough air for strong convection currents. The vapors condense in the chamber and are returned.

When the locomotive is moving along the track the pump is in operation and this produces a strong blast of air or jet which passes through the opening 24 and into the passageway 29 thereby forcing a blast of air into the retort and causing a puff of smoke to be blown out. When the piston of the pump descends, air is drawn in through the holes 24 but as these holes are not in communication with the hole 29 there is no reverse suction of air from the retort chamber to the pump. This avoids wasting the smoke-producing material and keeps it out of the pump or the interior of the locomotive.

Since it is obvious that the invention may be embodied in other forms and construction within the scope of the claims, I wish it to be understood that the particular forms shown are but a few of these forms, and various modifications and changes being possible, I do not otherwise limit myself in any way with respect thereto.

What is claimed is:

1. In a toy smoke-producing apparatus, in combination, a pump having a reciprocating piston and a cylinder having a tiny port in its end, through which air compressed in the cylinder escapes as a jet, and a smoke generating retort fixedly disposed relative to the pump and provided with an exhaust flue and having an injection passageway with its inlet end open to the atmosphere for aspiration of air in addition to the air in the jet and transmitting the same into the retort, the passageway being aligned with the port to accept the jet of air expelled therethrough and the entrapped air but spaced from the port so that air can enter the cylinder through the port without going through the passageway.

2. A toy smoke-producing apparatus as claimed in claim 1, wherein the flue is vertical and above the bottom of the retort to admit smoke-producing material and the retort has an electric resistance heater.

3. A smoke-producing toy locomotive having driving wheels, a cam driven with the wheels, a fixed cylinder, a reciprocable piston in the cylinder drivingly connected to the cam, the cylinder having a tiny port in its end through which air compressed in the cylinder escapes as a jet, a retort fixedly disposed relative to the cylinder spaced from the end of the cylinder and having a passageway aligned with the port and its adjacent end open to the outside air so that on the suction stroke of the piston air enters through the port without going through the passageway and on the compression stroke the expelled air forms a jet adapted to enter the passageway, the retort having a smoke generating chamber into which the passageway opens and an exhaust port for expulsion of vapors.

4. In a smoke-producing toy, a housing having a cup-shaped receiver for smoke-producing material, the housing wall having a vertical passageway lateral of and close to the receiver and opening downwardly and upwardly, a cover over the

housing, the cover being spaced above the upper end of the passageway and having an exhaust flue, an electric heater in the receiver, and means for producing intermittent one way blasts of air directed upwardly through the passageway.

5. In a smoke-producing toy, a housing having a cup-shaped receiver for smoke producing material, the housing wall having a vertical passageway lateral of and close to the receiver and opening downwardly and upwardly, a cover over the housing, the cover being spaced above the upper end of the passageway and having an exhaust flue, an electric heater in the receiver, and a reciprocating pump fixedly disposed relative to the receiver and having a jet forming port aligned with but spaced from the lower end of the passageway.

6. A device for producing a succession of puffs of smoke to simulate the smoke from a locomotive stack which comprises a smoke generating retort having an electrically heated receiver for smoke producing material whereby the retort may be kept filled with smoky vapors, an exhaust flue above the receiver, means providing a relatively small air injection passageway with its outlet end opening into the retort and its inlet end open to the atmosphere so that fresh air may enter the retort through the same, and means for effecting unidirectional intermittent blasts of fresh air through the inlet opening of the injection passageway to expel some of the vapors through the flue.
